METHOD AND MACHINE FOR METAL-
WORKING

Marion L. Strawn and Rene Louis Rougemont,
Rockford, Ill., assignors to The Ingersoll Mill-
ing Machine Company, Rockford, Ill., a cor-
poration of Illinois

Application November 25, 1935, Serial No. 51,406

43 Claims. (Cl. 29—33)

One object of the invention is to provide a new and improved method of conditioning certain types of work-pieces for the performance of metal-removing operations thereon and comprising generally flexing the work piece to bring a face thereof into a condition to be machined, and while maintaining the piece in such condition, performing a metal-removing operation on the conditioned face.

10 Another object is to provide a novel method of preparing deformable metal bars such as billets of copper or the like for the performance of drawing operations thereon.

The invention also resides in the novel character of certain of the mechanisms used in carrying out the foregoing objects.

While the present invention may be applicable to various industries, it will be herein described in connection with the operations required for 20 preparing a billet for wire drawing.

Metal which is intended to be drawn into wire is cast in molds that produce billets or "wire bars" which, in the case of copper billets, have the cross-sectional form indicated in Fig. 4 of 25 the present drawings, *a* being the bottom, *b* the sides, and *c* the upper surface of the billet. As shown in Fig. 5, the opposite ends of the billet have tapered surfaces *d*. The upper surface *c* contains considerable slag and is hard and scaly, 30 and it should be removed before the billet is drawn into wire. It is important, also, that the billet contains no sharp corners, as such corners tend to produce folds or seams in the drawing operation and ultimately cause breaks in the wire.

35 While the billet is cooling and shrinking, it usually becomes warped in one or more directions.

The general object of the machine illustrated in the present drawings is to prepare a wire bar or billet for wire drawing. In the case of copper billets, such preparation includes the straightening of the billet, the removal of the upper surface *c*, and the rounding of the square side edges produced in the removal of the upper surface. 40 The machine is largely automatic. Straightening and clamping of the billet are effected at a loading station under manual control, after which the operator closes an electric circuit which causes the machine to go through a fixed cycle of operations, during which the upper surface and the two square corners above referred to are milled off, whereupon the machine stops. The billet is then released and discharged from the carriage on which it was mounted. The operator then closes the before-mentioned switch and

thereby causes the carriage to return to the loading station where another billet has in the meantime been placed in position to be clamped in the carriage.

In the accompanying drawings:

5 Figure 1 is a perspective view of a machine embodying the features of our invention. In this view the carriage, by means of which the billet is carried past the cutters, is shown at the unloading station.

10 Fig. 2 is a fragmental side elevation of the machine, showing the carriage at the loading station.

15 Fig. 3 is a diagrammatic view of the hydraulically actuated mechanisms.

Fig. 4 is a view which illustrates, more or less diagrammatically, the clamping and milling of the billet.

20 Fig. 5 is a side elevation showing in dotted lines the original form that a billet may have, and showing the horizontal and vertical straightening rams in operation upon the billet to impart to it the straightened form indicated in full lines.

Fig. 6 is a fragmental vertical sectional view taken in the plane of line 6—6 of Fig. 2.

25 Fig. 7 is a horizontal sectional view taken approximately in the plane of line 7—7 of Fig. 6 with certain parts broken away.

Fig. 8 illustrates diagrammatically the relative movement between the billet and the edge-rounding cutters.

30 Fig. 9 is a horizontal sectional view in the plane of line 9—9 of Fig. 2.

Fig. 10 is a vertical section on line 10—10 of Fig. 9.

35 Fig. 11 is a horizontal section on line 11—11 of Fig. 10.

Fig. 12 is a diagram of the entire machine to show the cycle of operations and the electrical circuits.

40 Figs. 13 to 20 show successive positions of certain carriage-dog-actuated switches.

Fig. 21 is an elevation looking from the left-hand end of Fig. 2 and showing the carriage approaching the unloading station.

45 Fig. 22 is a fragmental elevation looking from the opposite side of Fig. 21.

Fig. 23 is a fragmental elevation looking from the right-hand side of Fig. 22.

50 The embodiment herein shown of the invention comprises an elongated bed 1. At the right-hand end of the machine, as viewed in Fig. 1, is a loading station, at the opposite end is an unloading station, and between these two stations is arranged a set of milling cutters. The billet is car-

55

ried from the loading station to the unloading station upon a carriage 2 having secured to its lower side two tubular guides 3 (Fig. 6) which slide in concave ways 4 formed in the bed. The carriage is traversed by means of a screw 5 extending lengthwise of and rotatably mounted in the bed, and engaging a partial nut 6 on the carriage.

Referring now to the means for straightening and clamping the billet and for locating it so that a cut of predetermined thickness shall be removed from it:

At the loading station there is an upstanding frame portion 7 (Figs. 6 and 7) on which is a horizontal surface 8 upon which rests an adjustable abutment in the form of an elongated casting 9. This abutment carries three blocks 10 against which the slag side c of the billet is to be pressed in the straightening operation. The blocks also constitute a positioning gage which operates during straightening to so locate the billet in its supporting fixture preparatory to clamping that a predetermined thickness of metal will be cut from the slag side in the metal-removing operation. The abutment 9 carries two arms 11 pivoted on the axes 12 and normally held perpendicular to the abutment by means of contractile springs 13. Stop lugs 14 on the abutment 9 limit the action of the springs. The arms 11 serve to support the billet until the arrival of the carriage 2 at the loading station. At one end of the abutment 9 is an adjustable stop 14^a (Figs. 1 and 7) for one end of the billet.

The abutment 9 is arranged for horizontal adjustment to position the blocks 10 in such relation to the cutters as to determine the depth of the cut. The means herein shown for thus adjusting the abutment or positioning gage 9 comprises two screws 15 (Fig. 7) rotatably connected 40 to the abutment 9 at one end and held against endwise movement with reference to the abutment. The screws 15 extend through nuts 16 fixed in the frame portion 7. The screws 15 are connected for rotation in unison by means of 45 worm wheels 17 splined to the screws and held on the frame portion 7 against endwise movement with relation to the frame. The worm wheels 17 mesh with worms 18 on the shaft 19 carried by the frame portion 7. To one end of the shaft 19 is 50 attached a hand wheel 20. On one of the screws 15 is an adjustable stop collar in the form of a split nut 21 threaded onto the screw and arranged to be locked thereon by turning a handle 21^a. As the hand wheel 20 is turned to advance the abutment 9, the collar 21 engages the portion 22 of the frame member 7 to locate the abutment 9 in its predetermined forward position.

23 is a pointer secured to the abutment 9 and coacting with a series of graduations 24 on the frame portion 7 to indicate the amount of stock to be removed.

The present embodiment of the invention has been arranged so that if desired it could be readily rearranged to operate upon two billets at a time,—one billet at each side of the carriage. With this in view there is located opposite the loading station a frame member 25 (Fig. 6) which is substantially similar to the frame member 7 and which is arranged to coact with elements on the carriage. If the machine were to be arranged to operate upon two billets at a time, there would be a loading station on the frame portion 25 similar to that on the frame portion 7, and each abutment 9 would take the thrust of the straightening devices at the opposite side, but in the pres-

ent instance the frame portion 25 is not equipped with an abutment like the abutment 9, said frame portion being merely provided with a simple abutment to take the thrust of the devices that straighten the billet at the loading station illustrated.

On the carriage 2 is mounted apparatus which would be in duplicate if the machine were intended to operate upon two billets at a time, but in the present instance the carriage is provided at 10 one side with means for straightening and clamping a billet at the loading station herein described, together with means to coact with the frame portion 25 to take the thrust during the straightening operation.

The straightening and clamping devices are hydraulically actuated. Upon the carriage 2 is mounted a structure 26 (Fig. 6) in the lower portion of which are formed three horizontal cylinders 27. In each cylinder 27 are two pistons 28 and 29. To the piston 28 is fixed a ram or piston rod 30 adapted to bear against the surface a of the billet and press the surface c against the blocks 10, thereby removing any bend in said surface. As shown in Fig. 7, there is a block 10 opposite each of the rams 30. Expansive springs 31 (Fig. 6) normally retract the rams 30 until stop collars 32 on the rams stop against the ends of the cylinders.

To the piston 29 are fixed piston rods 33 (Figs. 30 1 and 6) which are arranged to bear against an abutment bar 34 that is adjustably secured to the frame portion 25. Springs 35 (Fig. 6) normally retract the piston rods 33 until stop collars 35 36 on the piston rods stop against the ends 37 of the cylinders 27.

38 (Fig. 6) is a reservoir in the structure 26, and 38^a is a pump, said reservoir and pump being placed in communication with the cylinders 27 in any preferred manner, as, for example, that 40 diagrammatically indicated in Fig. 3 and hereinafter referred to. The pump 38^a is continuously driven by an electric motor 38^c mounted on the structure 26.

The carriage 2 is provided with three blocks 39 45 (Figs. 5 and 6) on which the billet lies while it is being straightened and against which it is clamped and held during the milling operation. In the structure 26 are formed three cylinders 40 50 in which are pistons 41 to which are connected piston rods 42 that are arranged to bear against a surface b of the billet. As shown in Fig. 5, there is a supporting block 39 directly below the points against which the piston rods 42 exert 55 pressure to straighten and clamp the billet. The lower ends of the piston rods 42 and the upper surfaces of the blocks 39 are preferably serrated, as shown in Fig. 4, to afford an effective grip upon the billet. Springs 43 normally retract the piston 60 rods 42.

The cylinders 40 are arranged to be connected to the reservoir 38 and the pump 38^a in any desired manner, as, for example, that diagrammatically illustrated in Fig. 3.

As the carriage arrives at the loading station the corner 43^a (Fig. 22) on the forward end of the carriage engages the projecting ends of the arms 11 and swings said arms into the position shown in Fig. 7. The surface 43^b (Figs. 6, 21 and 70 22) on the carriage holds the arms 11 in such position. The travel of the carriage also places the blocks 39 under the billet, said blocks passing under the tapered ends of the billet, raising the billet, if necessary, and said blocks serving to 75

support the billet after the arms 11 have been pushed into the position shown in Fig. 7. The rams 30 are then actuated to press the billet against the blocks 10, after which the piston rods 5 42 are actuated to press the billet against the blocks 39 and clamp the billet.

The milling mechanism is supported upon a column 44 (Figs. 1 and 2) which forms a part of the machine frame. There are three cutters, 10 all mounted for rotation upon horizontal axes, the face milling cutter 45 serving to mill the surface c of the billet and the shaped cutters 46 acting to bevel the square corners produced by the operation of the cutter 45. It will be understood from Figs. 1 and 2 that the billet first engages the cutter 45 and then travels into engagement with the cutters 46. As used herein, the term "bevel" contemplates rounding, chamfering, or otherwise cutting off the metal from the edges of the machined face of the billet so as to eliminate sharp corners that might prevent proper drawing.

The means herein shown for driving the cutters 45 and 46 comprises an elongated form 25 47 that meshes with a worm wheel 48 (Fig. 12) to which the cutter 45 is rigidly connected, and worm wheels 49 to which the cutters 46 are rigidly connected. The worm 47 is driven by means of a belt 50 and a motor 51.

The spindles upon which the cutters 46 and the worm wheels 49 are fixed are rotatably supported in slides 52 (Fig. 12). One of said slides is shown in dotted lines in Fig. 9. They are mounted in the column 44 for vertical movement 30 toward and away from each other so as to position the cutters 46 properly with relation to the varying widths of the billet. For this purpose the slides 52 are provided with fixed nuts which engage oppositely threaded screws 53 which are rigid with a shaft 54. In the construction herein shown, the shaft 54 is driven from a shaft that drives the feed screw 5, which shaft rotates continuously during the travel of the carriage.

In order that the cutter slides 52 shall be moved to and held in a certain fixed position during the milling of the main body of the billet, we provide a drive capable of slipping and means for positively limiting the rotation of the shaft 54 in either direction.

Referring now to Figs. 10 and 11: Rigidly fixed to the shaft 54 is a disk 55 to the periphery of which are adjustably secured two stop blocks 56. On the machine frame is fixed a stop 57 adapted 55 to be engaged by one of the blocks 56 when the shaft 54 has completed its movement in one direction and arranged to be engaged by the other block 56 upon the completion of the movement of the shaft 54 in the opposite direction. A worm wheel 58 is rotatably mounted upon the shaft 54 and is arranged to drive said shaft through a friction clutch 59 comprising a plurality of disks, alternate disks being splined to the shaft and the worm wheel, and the set of 60 disks being yieldingly pressed together by means of springs 60. The worm wheel 58 meshes with a worm 61 (Fig. 9) on a shaft 62, said shaft being driven from a shaft 63 through reversing gears 64. These gears are arranged to be alternately 65 clutched to the shaft 62 by a slideable clutch member 64a. The member 64a is normally held in neutral position by springs 64b and 64c. The shaft 63 is driven through a change gear train 65 from a shaft 66. The shaft 66 is geared to

a shaft 67 which, as before stated, is the shaft through which the screw 5 is driven.

The speed of the carriage 2 is arranged to vary as indicated in the diagram, Fig. 12. The means whereby the shaft 67 is driven to produce such variations in carriage feed may be of any desired construction, but preferably is of the general character illustrated in the Oberhoffken Patent No. 1,902,179, dated March 21, 1933, and the Oberhoffken application Serial No. 723,136, filed April 30, 1934.

Referring to Fig. 12: The shaft 67 is rigid with a spider or planetary carrier 68 that carries a plurality of planetary gears 69, only one of which is shown in the diagram. The planetary gears mesh with a sun gear 70 fixed to the shaft 71 of the rapid traverse motor 72. The planet gears also mesh with a ring gear 73 which is driven by a worm 74, a change gear train 75 and a feed motor 76. When the rapid traverse 20 motor 72 is not to operate, the shaft 71 is held against rotation by means of a brake 77.

The feed motor operates continuously during the travel of the carriage, and by reason of the gear reduction shown the shaft 67 is driven at a 25 relatively low speed, thus moving the carriage at the proper rate during the milling operation.

The rapid traverse motor 72 is operated in conjunction with the feed motor 76 to drive the shaft 67 to produce a relatively rapid movement 30 which is employed to effect a rapid approach of the work to the cutters, a rapid movement of the carriage after the work has passed the cutters to the unloading station, and a rapid return from the unloading station to the loading station. 35

The circuit of the feed motor 76 is closed through the medium of a push button switch 78 (Fig. 12) to inaugurate movement of the carriage from the loading station to the unloading station 40 and to close the circuit of the cutter driving motor 51. During such travel dogs on the carriage 2 operate a pawl-and-ratchet mechanism to produce intermittent rotation of a set of cams which operate switches to produce the desired changes 45 in carriage speed and the movement of the cutters 46 toward and away from each other. These cams are shown in Fig. 12 and their positions of rest are illustrated in Figs. 13 to 20.

Upon arrival of the carriage at the unloading 50 station, a dog on the carriage operates the set of cams to stop the motors. To return the carriage to the loading station, the operator again operates the push button 78, which this time closes the circuit of the rapid traverse motor 72 55 and thus causes the carriage to be rapidly returned to the loading station.

The diagram, Fig. 12, illustrates the circuits as arranged when the carriage is at rest at the loading station. The dog-actuated switches occupy the positions shown in Figs. 12 and 13. Closure of the switch 78 establishes a circuit as follows: Line L¹, conductor 81, relay coil 82, conductor 83, switch 78, conductor 84 and line L².

The energization of the relay coil 82 closes the 65 relay switch 85 which establishes a circuit as follows: Line L¹, conductors 97^a and 98, switch 95, coil 96 of relay 97, conductor 99, switch 100, conductor 91, switch 92, conductor 93, switch 94, and conductor 96 to line L².

The closing of the relay switch 95 establishes another circuit as follows: Line L¹, conductors 97^a and 98, switch 95, conductor 85, coil 86 of relay 87, conductor 86, switch 89, conductors 90 and 91, overload relay switch 92, conductor 93, nor- 70 75

normally closed switch 84 and conductor 84 to line L². The relay 87 controls the supply of current to the feed motor 76.

The closing of the relay coils 86 and 96 causes current to be supplied to the feed motor 76 and the rapid traverse motor 72, whereupon the carriage 2 is advanced rapidly until the billet is close to the cutter 46.

The closing of the push button switch 78 also closed a circuit as follows: Line L¹, conductors 97^a and 98, switch 95, conductors 85 and 101, solenoid 102, conductor 103, switch 104, conductors 105, 106 and 91, switch 92, conductor 93, switch 94, and conductor 84 to line L². The solenoid 102 thereupon shifts the reversing gear clutch 64^a to initiate movement of the cutters 46 toward each other, as indicated by the dot and dash lines 107 in the upper left-hand portion of Fig. 12.

As the cutters 46 reach the point of closest approach to each other, a dog 108 on the carriage 2 actuates a pawl-and-ratchet mechanism 109 to turn the set of cams from the position shown in Figs. 12 and 13 to that represented in Fig. 14. The switch 103 is thereby opened, thus deenergizing the solenoid 102 and permitting the spring 64^b to shift the reversing gear clutch to neutral and stopping the approaching movement of the cutters 46.

As the carriage 2 continues its rapid approach, a dog 110 on the carriage actuates the mechanism 109 to turn the set of cams to the position shown in Fig. 15, thus opening a switch 111 in the circuit of the rapid traverse motor 72. The carriage continues to advance, but at the slower feed rate, to carry the billet past the cutters 45 and 46.

As the leading end of the billet reaches the cutters 46, a dog 112 on the carriage actuates the mechanism 109 to turn the set of cams to the position shown in Fig. 16, thereby closing a switch 113 and thus establishing a circuit as follows: Line L¹, conductors 97^a and 98, switch 95, conductors 85 and 101 to solenoid coil 114, conductor 115, switch 113, conductors 106 and 91, switch 92, conductor 93, switch 94 and conductor 84 to line L². The clutch member 64^a is thereby moved to cause the shaft 62 to be driven in the direction to move the cutters 46 apart. Since the shaft 62 is driven mechanically from the same source of power as the carriage feed mechanism, such separation of the cutters will occur in timed relation to the carriage movement so that the cutters will follow the tapering outline of the billet as the latter is fed along. The change gears 65 permit the feed rate of the cutters 46 to be changed to correspond to the taper of the billet to be operated upon.

When the cutters 46 have finished milling the corners of the tapered leading end of the billet, one of the stop blocks 56 (Fig. 11) strikes against the fixed stop 57 and arrests the separating movement of the cutters 46, the continued rotation of the worm wheel 58 (Fig. 10) serving to hold said stop block pressed against the fixed stop and thus holding the cutters 46 at a precise distance apart while the main body of the billet is fed past them.

As the tapered rear end of the billet approaches the cutters 46, a dog 116 on the carriage actuates the mechanism 109 to turn the set of cams into the position shown in Fig. 17, thereby opening the switch 113 and closing the switch 104, and thus causing the cutters 46 to approach each other.

As the billet passes beyond the cutters 46, a

dog 117 on the carriage actuates the mechanism 109 to turn the set of cams to the position represented in Fig. 18, thereby opening the switch 104 and closing the switch 113 and thus causing the cutters 46 to recede from each other. The switch 111 also is closed, thus restarting the rapid traverse motor 72 and causing the carriage to move rapidly toward the unloading station.

As the cutters 46 move apart, the other stop block 56 engages the fixed stop 57 and arrests the separating movement of the cutters when the latter are at a predetermined distance apart. A moment thereafter a dog 118 on the carriage actuates the mechanism 109 to turn the set of cams to the position illustrated in Fig. 19, thus opening the switch 113 and allowing the spring 64^c to place the clutch member 64^a in neutral.

As the carriage reaches the unloading station, a dog 119 on the carriage actuates the mechanism 109 to turn the set of cams to the position seen in Fig. 20, thereby momentarily opening the switch 100 to break the circuit of the coil 96 of the relay 97, and thus stopping all of the motors 51, 72 and 76, and bringing the carriage to rest at the unloading station. The switches 89 and 111 in the circuits that control the supply of current to the feed motor 76 and the rapid traverse motor 72, also are opened. A switch 120 also is closed, preparatory to the rapid return movement of the carriage.

After the billet has been unloaded, the operator again closes the push button switch 78 to initiate the return cycle. This completes a circuit as follows: Line L¹, conductor 81, coil 82 of relay 95, conductor 83, switch 78 and conductor 84 to line L². The closing of the relay switch 95 establishes a circuit as follows: Line L¹, conductors 97^a and 98, switch 95, coil 96 of relay 97, conductor 99, switch 100, conductor 91, switch 92, conductor 93, switch 94 and conductor 84 to line L². The closing of the relay 97 completes the circuit of the rapid traverse motor 72 and causes rapid return of the carriage 2 to the loading station.

The dogs 106, 110, 112, 116, 117 and 118 are pivotally mounted upon the carriage, stop pins 121 limiting pivotal movement in one direction and thus rendering the dogs effective in the travel of the carriage to the unloading station and ineffective in the return movement.

Upon the arrival of the carriage at the loading station, a fixed dog 122 on the carriage actuates the mechanism 109 to turn the set of cams to the position shown in Figs. 12 and 13, thereby causing a momentary opening of the switch 100 to break the circuit of the coil 96, and thus stopping the rapid traverse motor 72, whereupon the carriage comes to rest at the loading station. The switch 120 also is opened.

123 is a switch in the relay 97 arranged to close a circuit in parallel with the circuit of the switch 95, as follows: Line L¹, conductor 98, switch 123, conductor 124, normally closed safety limit switches 125 and 126 and conductor 127. The cams 89, 104 and 111 also are closed in readiness for the next milling cycle.

As before explained, upon closure of the push button switch 78 the relay coil 92 is energized to close the switch 95. This switch in turn completes a circuit to energize the coil 96 to close the relay 97. Upon closure of the relay 97, the switch 123 in parallel with the switch 95 is closed, thereby maintaining the circuit through the coil 96 intact when the operator releases the push button switch 78. When the operator takes his

finger off the push button 78 the coil 82 is de-energized and the switch 95 opens. The holding switch 123 will remain closed until either the stop button switch 94 or the switch 100 is opened. 5 Each of these deenergizes the coil 96, thereby permitting the switch 123 to open to break the holding circuit. The switch 123 remains closed as long as there is no interruption in any part of the circuit. Interruption of the circuit will immediately permit the switch 123 to open and to remain open, although the interrupting switch be again immediately closed.

The push button switch 94 may be used to stop the machine at any time.

15 The normally closed safety limit switches 125 and 126 are arranged to be opened by the dogs 119 and 122, respectively, in the event that the switch 100 has failed to interrupt the circuit of the relay coil 96. If the dog 122 has acted to 20 stop the carriage at the loading station, the operator, when starting the machine, must hold the push button switch 78 closed until the dog 122 permits the limit switch 126 to close. Similarly, when starting a return trip of the carriage, if the dog 119 has acted to open the limit switch 125, the push button switch 78 must be held closed until the dog 119 allows the switch 125 to close.

25 It will be seen that if the ratchet-operated cam mechanism should fail to open the switch 100 upon arrival of the carriage at the unloading station the circuit of the coil 96 will be opened by the switch 126, and that if said cam mechanism should fail to open the switch 100 when the carriage reaches the loading station, the coil 96 will be deenergized through opening of the limit switch 125.

30 Referring now to the means for operating the horizontal rams 30 and the vertical rams 42: 40 Any preferred arrangement of valves may be employed to connect the cylinders 27 and 40 to the reservoir 38 and the pump 38a. Herein I have shown a valve 127 operated by a handle 128 for controlling the operation of the rams 30. A 45 similar valve 129 controls the rams 42. The valve 129 is operated manually to clamp the billet at the loading station by means of a handle 130. Said valve is automatically operated to unclamp the billet before the carriage comes to rest at the unloading station by means comprising a 50 lever 131 (Fig. 22) mounted on the carriage, one arm of said lever being arranged to engage an arm 132 which is rigid with the handle 130. The other arm of the lever 131 is arranged to be moved by a plunger 133 mounted on the carriage for vertical movement. The upper end of the plunger 133 underlies an arm 134 which is fixed upon a shaft 135 on the carriage. The shaft 135 also carries an arm 136 located in position to engage a pin 137 on the column 44 as the carriage is approaching the unloading station. Engagement of the arm 136 with the pin 137 causes the valve 129 to be shifted to retract the clamping rams 42. A spring 138 connected 55 to the shaft 135 serves to hold the valve 129 in such position and also holds the arm 136 up into the position to which it has been moved by the pin 137.

70 Means is provided to automatically discharge the billet from the carriage as the carriage comes to rest at the unloading station. Said means comprises a rock shaft 139 (Figs. 3, 6 and 21) supported on the carriage 2 and having fixed thereon two arms 140 and a hand lever 141. The shaft 139 is arranged to be rocked to swing the

arms 140 against the billet to push the latter off the blocks 39 and onto a table 142 on the bed of the machine. The means for thus rocking the shaft 139 comprises a hydraulic cylinder 143 (Fig. 3) arranged to be controlled by a valve 144. 5 The valve 144 is arranged to be operated by two solenoids 145 and 146 (Figs. 12 and 21). These solenoids are connected into the line (herein shown as the wires L² and L³), and the supply of current to said solenoids is controlled by means of a switch 147. The dog 119 is arranged to shift said switch to close a circuit through the solenoid 145 to operate the valve 144 to cause discharge of the billet. When the carriage starts on its return to the loading station, the switch 15 147 returns to its normal position wherein the solenoid 146 is energized to cause retraction of the ejecting arms 140 into the position shown in Figs. 3, 6 and 21.

Summarizing the operation of the machine and 20 assuming that a billet is lying upon the arms 11 (Fig. 7) and that the carriage is returning to the loading station: As the carriage comes to the loading station it swings the arms 11 into the position shown in Fig. 7, the blocks 39 (Fig. 6) 25 passing under the billet into position to support the latter. When the carriage has stopped, the operator operates the handle 128 (Fig. 3) to cause the rams 30 to force the billet against the blocks 10 under sufficient pressure to distort or 30 flex the billet longitudinally and cause the slag surface thereof to conform to the contour defined by the surfaces of the abutments 10. Thus, the surface to be machined is straightened and thereby conditioned for scalping, being at the 35 same time spaced accurately from the effective cutting plane of the cutter 45. The operator then operates the valve handle 130 to cause the rams 42 to force the billet against the blocks 39, thereby 40 effecting any straightening that may be required in that direction, and clamping the billet against said blocks 39 so as to retain the billet distorted and in straightened condition. The operator then operates the valve handle 128 to allow the springs 31 to withdraw the rams 30 thereby 45 releasing the straightening pressure and freeing the billet for exposure of its straightened face preparatory to machining thereof. Next, the hand wheel 20 is rotated to withdraw the abutment 9 from contact with the billet. The operator then closes the push button switch 78 to 50 initiate a cycle of operations during which the carriage is advanced and the milling cutters actuated to remove the hard rough surface c of the billet and round the sharp corners thereby produced. 55

During the final rapid traverse of the carriage toward the unloading station, the arm 136 strikes the pin 137 and thus causes the valve 129 to be shifted to produce unclamping of the billet. As 60 the carriage comes to rest at the unloading station, the dog 119 operates the switch 147 to deenergize the solenoid 146 and energize the solenoid 145, thereby causing the arms 140 to push the billet off the blocks 39 and onto the table 142. 65 The operator then closes the push button switch 78 to inaugurate a return movement of the carriage to the loading station. As the carriage is leaving the unloading station, the dog 119 allows the switch 147 to return to normal position, there- 70 by causing the arms 140 to be retracted.

It will be seen that the machine herein disclosed is adapted to straighten and remove a surface layer from a work-piece such as a wire bar rapidly with a minimum of effort and atten- 75

tion on the part of the workmen. The machine is readily adaptable for operation upon work-pieces of different sizes or with varying end tapers. Since the side surface to be operated upon is, preparatory to clamping of the bar in the fixture, located against the gaging abutment and therefore positioned accurately with respect to the cutting plane of the face mill 45 regardless of thickness of the bar, layers of the same predetermined thickness will be removed from successive bars. In this way, removal of an unnecessary amount of metal in case the bars vary in thickness is avoided.

While the machine is illustrated in connection with the preparation of copper billets for wire drawing, it is readily adaptable for removing a surface layer from other types of work-pieces, such for example as aluminum castings or cakes preparatory to drawing or rolling thereof.

20 We claim as our invention:

1. A metal working machine having, in combination, an abutment, means for supporting a billet in front of the abutment, a carriage having a support for the billet, means for moving the carriage to place said support under the billet and to remove said supporting means from effective relation to the billet, means on the carriage for forcing the billet against the abutment, means on the carriage to clamp the billet against said support, and means for withdrawing the abutment from contact with the billet.

2. A metal working machine having, in combination, an abutment, means for supporting a billet in front of the abutment, a carriage having a support for the billet, means for moving the carriage to place said support under the billet and to remove said supporting means from effective relation to the billet, means to force the billet against the abutment to straighten the billet, means on the carriage to force the billet against said support to straighten the billet and clamp it against the support, and means for withdrawing the abutment from contact with the billet.

45 3. A metal working machine having, in combination, an abutment, means for supporting a billet in front of the abutment, a carriage having a support for the billet, and means for moving the carriage to place said support under the billet and to remove said supporting means from effective relation to the billet.

4. A metal working machine having, in combination, a support for a billet, an abutment adjacent to said support, means for forcing a billet lying upon said support against said abutment to straighten the billet, means for thereafter forcing the billet against said support to straighten the billet and clamp it against the support, means for retracting the abutment, and means for operating upon that surface of the billet which was forced against the abutment.

5. A metal working machine having, in combination, a support for a billet, an abutment adjacent to said support, means for forcing a billet lying upon said support against said abutment to straighten the billet, means for thereafter forcing the billet against said support to straighten the billet and clamp it against the support, and means for retracting the abutment.

70 6. A metal working machine having, in combination, a support for a billet, an abutment alongside said support, means for forcing a billet lying upon said support against said abutment to straighten the billet, and means for forcing the

billet down against said support to straighten the billet.

7. A metal working machine having, in combination, a support for a billet, an abutment alongside said support, means for moving a billet lying upon said support against said abutment, means for thereafter clamping the billet against the support, means for retracting the abutment, and means for operating upon that surface of the billet which was moved against the abutment.

8. A metal working machine having, in combination, a carriage, abutments at opposite sides of the path of the carriage, a hydraulic cylinder on the carriage, and two rams arranged to be forced in opposite directions by pressure in said cylinder, one of said rams being arranged to bear against one abutment and the other ram being arranged to force a work-piece against the other abutment.

9. A metal working machine having, in combination, an elongated abutment, a stop upon one end of the abutment, an arm pivoted upon the abutment and spring-held in position to support a work-piece with one end of the work-piece against the stop, and a carriage movable longitudinally of the abutment into position beneath the work-piece and arranged to deflect the supporting arm into ineffective relation to the work-piece.

10. A metal working machine having, in combination, an elongated abutment, a stop upon one end of the abutment, an arm spring-held in position to support a work-piece alongside the abutment with one end of the work-piece against the stop, and a carriage movable longitudinally of the abutment into position beneath the work-piece and arranged to deflect the supporting arm into ineffective relation to the work-piece.

11. A metal working machine having, in combination, an elongated abutment, a stop upon one end of the abutment, means to support a work-piece alongside the abutment with one end of the work-piece against the stop, and a carriage movable longitudinally of the abutment into position beneath the work-piece and arranged to move the supporting means into ineffective relation to the work-piece.

12. A metal working machine having, in combination, an elongated abutment, a stop upon one end of the abutment, means to support a work-piece alongside the abutment with one end of the work-piece against the stop, and a carriage movable into position beneath the work-piece and arranged to move the supporting means into ineffective relation to the work-piece.

13. A metal working machine having, in combination, a cutter, a positioning gage at one side of the cutter, a carriage to move a work-piece from a position adjacent the gage to the cutter, mechanism on the carriage for forcing the work-piece against the gage and clamping it to the carriage, and means for retracting the gage from contact with the work-piece.

14. A machine for machining a wire bar having tapered ends comprising means for removing one surface of the bar, two cutters for rounding the opposite edges produced in such removal, and means for moving said cutters toward and away from each other to follow the outline of the tapered ends, said means comprising a friction drive and means for positively limiting the separating movement of said cutters, said drive acting in conjunction with said limiting means to

hold the cutters separated at a predetermined distance.

15. A machine for machining a wire bar having tapered ends comprising means for removing one surface of the bar, two cutters for rounding the opposite edges produced in such removal, and means for automatically moving said cutters toward and away from each other to follow the outline of the tapered ends and for holding said cutters at a definite distance apart while said cutters are operating upon the edges between the tapered ends.

16. A machine for machining a wire bar having tapered ends comprising means for removing one surface of the bar, two cutters for rounding the opposite edges produced in such removal, means for automatically moving said cutters toward and away from each other to follow the outline of the tapered ends, and means for feeding the bar past said removing means and said cutters in a continuous rectilinear movement, said cutters moving apart as the leading tapered end passes therebetween, said separating movement ceasing after said tapered end has passed the cutters, and said cutters approaching each other as the trailing tapered end passes between them.

17. A metal working machine having, in combination, an elongated bed, means at one end of the bed constituting a loading station, means at the other end of the bed constituting an unloading station, a cutter intermediate said stations, a carriage reciprocable on said bed from one station to the other and having means to clamp a work-piece to be carried past the cutter and means at the unloading station for removing the work-piece from the carriage.

18. A metal-working machine having, in combination, a reciprocatory work-supporting carriage, an ejector on the carriage for pushing the work-piece off the carriage, a hydraulic ram on the carriage for advancing and retracting the ejector, a valve to control the ram, two solenoids to operate the valve, one solenoid being normally energized to effect retraction of the ejector, and means actuated in the travel of the carriage to energize the other solenoid to effect advancement of the ejector.

19. A machine for removing a surface layer of predetermined depth from a work-piece having, in combination, a cutter for performing a surface machining operation, a fixture for supporting a work-piece, a gage for locating said work-piece in said fixture with the surface to be operated upon spaced from the cutting plane of said cutter a distance equal to the thickness of the metal layer to be removed, power operated means to straighten said work piece against said gage and then clamp the positioned work-piece in said fixture, and means to effect relative movement between said cutter and said fixture longitudinally of said plane.

20. For removing a surface layer of predetermined depth from a work-piece, a milling machine having, in combination, a cutter, a work fixture, an abutment movable toward and away from the cutting plane of said cutter and providing a gaging surface spaced from said plane a distance equal to the thickness of the layer of metal to be removed from said surface, means by which said work-piece may be clamped in said fixture while engaging said surface, means by which said abutment may be retracted to permit operation of said cutter on said work-piece, and means to effect relative movement between said

fixtures and said cutter longitudinally of said cutting plane.

21. A machine for cutting the slag from the surface of a wire bar having, in combination, a movable work carriage with an abutment thereon against which one side of said bar may be pressed, a second abutment against which the slag surface of said bar may be pressed while the bar is in engagement with said first mentioned abutment, power actuated means operating to apply pressure at spaced points along said bar to press the latter against said second abutment, stationary means to sustain the reactionary pressure of said last mentioned means, and a second power actuated means operating at spaced points along said bar to press the latter against said first abutment.

22. A machine for cutting the slag from the surface of a wire bar having, in combination, a cutter adapted to perform a surface machining operation, an abutment against which the slag surface of said wire bar may be pressed to locate the same for operative association with said cutter, a second abutment positioned for engagement with one side of said bar while the latter is positioned against said first abutment, power actuated means acting at points spaced along said bar to press the same against said first mentioned abutment and thereby straighten the bar in one direction, and power actuated means operable to apply pressure along the bar to press the latter against said second abutment and thereby straighten the bar in transverse direction.

23. A machine for cutting the slag from the surface of a wire bar having, in combination, a cutter adapted to perform a surface machining operation, an abutment against which the slag surface of said wire bar may be pressed to locate the same for operative association with said cutter, a fixture for supporting said bar during operation thereon by said cutter, a second abutment on said fixture positioned for engagement with one side of said bar while the latter is positioned against said first abutment, power actuated means operable to apply pressure along the bar to press the latter against said second abutment and thereby straighten the bar in a transverse direction, and means to effect relative movement between said cutter and said fixture while said bar remains clamped in the latter by said power actuated means.

24. A machine for cutting the slag from the surface of a wire bar having, in combination, a cutter adapted to perform a surface machining operation, an abutment against which the slag surface of said wire bar may be pressed to locate the same for operative association with said cutter, a second abutment positioned for engagement with one side of said bar while the latter is resting against said first abutment, fluid pressure actuated means acting at points spaced along said bar to press the same against said first mentioned abutment and thereby straighten the bar in one direction, and fluid pressure actuated means operable to apply pressure along the bar to press the latter against said second abutment and thereby straighten the bar in a transverse direction, means to effect relative movement between said cutter and positioned bar, and means controlling said pressure actuated means to maintain the former inactive and the latter active during said relative movement.

25. A machine for scalping the slag surface of a wire bar having, in combination, two abutments

- positioned for engagement with said slag surface and one side surface of said bar, independent power actuated means to press said bar against the respective abutments whereby to straighten the bar in two transverse directions, and control means for causing operation of said last mentioned means in succession.
26. For scalping wire bars having tapered ends, a machine having, in combination, power actuated means for straightening a bar to be operated upon relative to two transverse directions, a cutter positioned to operate upon the slag surface of the straightened bar, means to effect relative feeding movement between said cutter and the straightened bar, two cutters positioned for engagement with the edges of the surface machined by said first mentioned cutter and shaped to form a bevel on said edges, and means operating in timed relation to said feeding movement to feed said cutters away and toward each other so as to follow the contour of said edges.
27. A machine for removing the slag layer from a wire bar having, in combination, a cutter for performing a surfacing operation, means to locate said bar in cutting relation to said cutter with the slag surface thereof spaced from the plane of the cutter a distance equal to the depth of the metal layer to be removed, means for effecting relative movement between said cutter and said bar in a direction longitudinally of the latter, two cutters positioned to engage opposite side edges of said bar after operation thereon by said first mentioned cutter and operating to bevel the side edges of the machined surface of the bar, and means operating in timed relation to the relative movements between said cutter and said bar to move said second cutters apart progressively during engagement thereof with one tapered end of said bar and toward each other progressively during engagement with the other tapered end while maintaining a fixed spacing of said cutters during engagement thereof with the intermediate portions of said bar.
28. In a metal working machine, in combination, a gaging abutment, means for pressing a bar or the like against the abutment to straighten the bar against the abutment, means to withdraw the abutment, and means to remove the straightened surface that was in contact with the abutment.
29. The method of straightening and scalping a bar or the like which consists in straightening the bar in one direction by pressing it against a gaging abutment; then, while the bar is still under pressure, straightening the bar in a direction transverse to the first direction by pressing it against another abutment; and then, while maintaining the last-mentioned straightening pressure, withdrawing the first-mentioned straightening pressure and the gaging abutment and scalping the straightened surface that was in contact with the gaging abutment.
30. A machine for scalping a billet comprising means for distorting the billet to straighten one longitudinal surface thereof, means operating on the billet in a different direction from said first mentioned means to hold the billet in distorted condition, and cutting means to perform a metal removing operation on said surface while the latter is retained in straightened condition.
31. A machine for operating upon a work piece having a face to be machined having in combination, means engaging said face and an opposed portion of the work piece for applying pressure thereto sufficient to flex the piece and bring the face into condition to be machined, means operating upon a different portion of the piece to clamp the same in such flexed condition, said first mentioned means being releasable to relieve said pressure and expose said face for machining, and cutting means for machining said face while the piece is so clamped.
32. A machine for operating upon a deformable metallic work piece having in combination, two abutments arranged to engage angularly related faces of said work piece, means for pressing said piece against one of said abutments with sufficient pressure to cause the abutment engaging surface of said piece to conform to the contour defined by said abutment, means for pressing the work piece against the other abutment with sufficient pressure to retain said surface of the work piece in such conforming condition, said first mentioned means being releasable to separate the work piece and first abutment from each other to expose said surface, and cutting means for machining such exposed surface while it is maintained in said conforming condition.
33. A machine for scalping a metal bar, having, in combination, means for exerting pressure on opposite sides of the bar to flex the same into a condition to be operated upon, means for applying pressure in a transverse direction to opposite sides of the bar to clamp the bar and maintain it in flexed condition, said first mentioned means being releasable to expose one face of the bar, and cutting means operable while the bar is clamped in said second means to remove a layer of metal from said face.
34. A machine for scalping a deformable bar of metal having, in combination, an abutment having a face disposed in a predetermined plane, means to press said bar against said face with sufficient pressure to straighten the abutment engaging surface, means to clamp the bar in straightened condition, cutting means having an effective cutting face disposed in a plane intersecting the clamped bar and extending parallel to said first mentioned plane a distance therefrom predetermined by the thickness of the layer to be scalped from said surface, and means operating while the bar is so clamped to bring the bar and cutting means into cutting engagement with each other.
35. A machine for scalping a metal billet having a face with tapered ends comprising, in combination, means for clamping the billet in flexed or distorted condition to present said face in a predetermined plane, a tool for scalping a layer of metal from said face, a pair of tools for beveling the edges of said face, means for causing relative movement between the billet and all of said tools in one direction, and means for causing relative movement between the billet and the beveling tools to cause the latter to follow the contour of said tapered ends.
36. A machine for scalping billets having, in combination, loading and unloading stations, a carriage movable back and forth to carry a billet from the loading station to the unloading station, power actuated means on said carriage to clamp a billet thereon, cutting means operable to perform a metal removing operation on the billet during movement of said carriage from said loading station to the unloading station, means operating automatically after operation of said cutting means to release said clamping means, and power actuated means operating automatically to move the unclamped billet off from said carriage at said unloading station.

37. The method of machining one face of a metallic work piece which comprises flexing said work piece by pressure in a direction substantially normal to said face, holding the work piece in 5 such flexed condition, and machining said face while the work piece is so held.
38. The method of machining a piece of metal which comprises flexing the piece by pressure into a predetermined position to be machined, clamping the piece in such position, then releasing the 10 flexing pressure, and finally machining the piece while so clamped.
39. The method of scalping a bar of metal which comprises distorting the bar to straighten 15 one longitudinal surface thereof, holding the bar in distorted condition, and performing a metal removing operation on said surface while the latter is retained in straightened condition.
40. The method of operating upon a deformable metallic work piece which comprises pressing said piece against an abutment with sufficient pressure to cause the abutment engaging surface of said piece to conform to the contour defined by said abutment, then pressing the work 20 place against another abutment in a direction angularly related to the direction of the first mentioned pressure and with sufficient pressure to retain said surface of the work piece in such conforming condition, then separating said work 25 piece and first abutment from each other to expose said surface, and finally machining such ex-
- posed surface while it is maintained in said conforming condition.
41. The method of operating upon a work piece having a face to be machined which comprises engaging said face and an opposed portion 5 of the work piece and applying pressure thereto to flex the piece and bring the face into condition to be machined, clamping the piece while in such flexed condition, then releasing said flexing pressure to expose said face for machining, 10 and finally machining said face while the piece is so clamped.
42. The method of machining a piece of metal which comprises clamping the piece in flexed or distorted condition to present a face of the piece 15 in a plane to be machined, removing a layer of metal from said face and also contouring the edges of said face, while the piece is retained in said condition.
43. The method of scalping a metal billet having a face with tapered ends which comprises clamping the billet in flexed or distorted condition to present said face in a plane to be machined, removing a layer of metal from said face and beveling the edges of said face along its 20 sides and tapered ends, such removing and beveling being performed while the piece is retained in such flexed or distorted condition.
